INVENTOR.
Walter A. Frantz
BY
Harold E. Smith
ATTORNEY.

UNITED STATES PATENT OFFICE.

WALTER A. FRANTZ, OF CLEVELAND, OHIO.

WRINGER.

Application filed March 20, 1922. Serial No. 545,146.

To all whom it may concern:

Be it known that I, WALTER A. FRANTZ, a citizen of the United States, residing at Cleveland, in the county of Cuyahoga and State of Ohio, have invented a certain new and useful Improvement in Wringers, of which the following is a full, clear, and exact description, reference being had to the accompanying drawings.

10 This invention relates to clothes wringers and has for its objects the provision of a new and improved drain and guide-board which shall facilitate the wringing operation, decrease slopping and splashing of the water, and cause the clothes to come from the wringer in drier condition; the provision of a new and improved construction and support for a splash board; the provision of a new and improved device for guiding the clothes and discharging them at a distance from the rolls; while further objects and advantages will become apparent as this description proceeds.

25 In the drawings accompanying and forming a part of this application I have shown one of the many physical forms in which my inventive idea can be embodied although it will be understood that this drawing is illustrative only and not limiting upon me.

30 Fig. 1 is a side elevation of a wringer provided with my improvements; Fig. 2 is a sectional view on the line 2—2 of Fig. 1; Fig. 3 is a face view of one of the end plates; and Fig. 4 is a detail sectional view corresponding to the line 4—4 of Fig. 3.

40 Describing the parts by reference characters, 1, 1 represent upright end members of a wringer frame 2, 2 the rolls journaled thereon, and 4 the bottom member of the frame which connects the end members. 3 represents the tub or casing upon which the wringer is mounted. I have shown this frame as being made of metal, although my improvements are not restricted to use with such a frame. The sides of the members are slanted to constitute guides to the rolls and the bottoms of said members are formed with the spaced opposed flanges 5, 5 constituting slides.

50 My improved splash-board comprises an upper guiding and supporting shelf or portion 7 over which the clothes are fed to the rolls, and a lower shelf or portion 9 arranged to return the water to the tub or casing out of contact with the clothes; preferably also

comprising a guiding part 7^a to lead the clothes away from the wringer. In this embodiment all these parts are approximately symmetrical and are formed by bending a single piece of sheet metal, the portions 7 and 9 being connected by an integral bend 8, and the portions 7^a and 9^a being connected by the integral bend 8^a. The uppermost ends of the portions 7 and 7^a are fashioned to engage the wringer in any suitable way, 60 as by being formed with lips 6, 6^a, respectively adapted to engage the flanges 5, 5. The lip 6^a is shown as extended to produce a partition 10 sloped to shed water onto the shelf portion 9, from which it is returned to 70 the tub by the opening 12.

75 In the preferred form this sheet metal plate is clamped by bolts 13, 13 between cast metal end-plates 14, 14, whose inner faces are formed with grooves for the sheet metal. The margins of these end plates are formed with flanges 15 constituting guides for the clothing. The slope of the portions 7, 7 is so chosen that the clothes will pass over them properly either toward or from the rolls; 80 the slope of the portions 9, is unimportant except that it must drain toward the tub or casing and the holes 12 are located at that side toward which the partition 10 drains. The flanges 5, 5 are here shown as extending 85 to the end of the wringer frame as in Fig. 1 so that the device can be slid endwise for removal or reversal, although I do not restrict myself to this mode of mounting.

90 My improvements are especially important in cases where it is desired to have the clothes-guide extend a considerable distance from the wringer as is often the case in power operated washing machines. In these cases it is desirable to separate the outgoing clothes from the returning water, else the same water has to be wrung out of the clothes repeatedly. It is also frequently desirable to guide the clothes a considerable distance away from the wringer, this also most frequently occurring in power operated washing machines. And it is desirable that the device be symmetrical so that it can be applied in either direction and the wringer run either way.

100 It will be understood that many changes can be made in the detail structure of the device, both in material, design, mode of construction, mode of attachment, width, height, and appearance, so that I do not 105

limit myself in any wise except as specifically recited in my claims:

Having thus described my invention what I claim is:

- 5 1. As an article of manufacture, a member adapted to be attached outside the bottom of a wringer frame and to project laterally of said frame at both sides, the projecting portions being sloped downwardly from the wringer rolls so as to form chutes, and a shelf portion beneath one of said chutes adapted to return water from the rolls to a tub independently of the chute.
- 15 2. As an article of manufacture, a member adapted to be attached outside the bottom of a wringer frame and to project laterally of said frame at both sides, the projecting portions being sloped downwardly from the wringer rolls so as to form chutes, a laterally sloped water discharge shelf located beneath one of said chutes, and means for directing the expressed water toward said shelf whereby the same may be returned to the tub independently of the chute.
- 20 3. In a device of the character described, in combination, a wringer frame having a longitudinal slideway on its bottom member, and a device slidably and reversably engaging said slideway, said device having clothes

guiding portions projecting laterally in an inclined direction at each side of the wringer rolls, and also having a drip receiving shelf located beneath one of said guiding portions adapted to carry all the drip away from the rolls in one direction.

35 4. A clothes wringer attachment comprising a pair of end plates and a sheet metal part clamped between them, said sheet metal part defining a pair of oppositely extending inclined chutes and a drip shelf beneath one of said chutes, and means for securing said attachment to a wringer frame with the respective chutes at opposite sides thereof.

5. A clothes wringer attachment comprising a pair of end plates and a sheet metal part clamped between them, said sheet metal part being folded to form a bilaterally symmetrical hollow casing, the top sides of which constitute clothes chutes, and an inclined partition extending from the upper edge of one of the chutes to the bottom of the casing beneath the other chute and defining with such bottom a drip board, such bottom being apertured for the discharge of water falling thereon.

50 55 In testimony whereof, I hereunto affix my signature.

WALTER A. FRANTZ.
